PAPER PLEATING MACHINE

Fred Schwartz, Green Bay, Wis., assignor to Fort
Howard Paper Company, Green Bay, Wis., a
corporation of Wisconsin

Application May 6, 1935, Serial No. 20,064

3 Claims. (Cl. 154—30)

The invention relates to machines for pleating paper and has as an object the provision of paper that is stretchable transversely, and by virtue of the fact that the paper treated by the machine is preferably first corrugated transversely before being pleated longitudinally, the resulting paper is stretchable in both directions, and may be used as a lining for barrels, sacks, or the like.

It is a further object of the invention to provide a machine for pleating paper by the use of elastic belts succeeded by forming devices and pressure rolls to finally complete the pleats.

Further objects of the invention will appear from the following description when read in connection with the accompanying drawings showing an illustrative embodiment of the invention, and wherein:—

Figure 1 is a plan view;

Fig. 2 is a vertical section on line 2—2 of Fig. 1;
Fig. 3 is a plan view of a portion of a pleat designed to coat with the elastic belts;

Fig. 4 is a perspective view of one of the final pleating blocks;

Figs. 5, 6, 7, 8, and 9 are detail transverse sections on the corresponding section lines of Fig. 2;

Fig. 10 is a side elevation illustrating the roll driving mechanism; and

Fig. 11 is a detail cross section of the paper produced by the machine.

As shown the device comprises a pair of corrugated rolls 12, 13 mounted in standards 14, one of said rolls being provided with a sheave 15 by which the device is driven, and the rolls 12, 13 provided with interengaging gears 16 for drive of the roll 12 from the roll 13. There are also provided upper and lower rolls 17, 18, and 19, 20, which are corrugated with the same number of corrugations as those of the rolls 12, 13, but in which the corrugations are more closely spaced than in the first named rolls. The respective pairs of rolls 12, 13, 17, 18, and 19, 20, have their adjacent surfaces in alignment.

Mounted to travel in the corrugations 21, 22 of the rolls, there are shown belts 23, 24. The belts for the upper and lower rolls respectively are shown as staggered. Because of the fact that the corrugations 21 and 22 in the rolls 17, 18, and 19, 20 are more closely spaced than those of the rolls 12, 13, a web of paper 25 fed between the belts upon the rolls 12, 13 will have its width reduced in its travel from rolls 12, 13 to the rolls 17, 18.

To guide the paper during its width-narrowing travel, there are shown upper and lower corrugated plates 26, 27 having corrugations to re-

ceive and guide the belts 23, 24 and the paper extending over and under the successive belts transversely of the machine.

The plates 26, 27 are shown as mounted in the standards 14 and the standards 28, 29, the latter supporting the rolls 17, 18 and rolls 19, 20 respectively by means of brackets 30, 31 respectively and provided for necessary adjustment toward and from each other by slotting of the vertical portions of the brackets. 10

The paper leaving the rolls 19, 20 is immediately received between spaced vertical pleating blocks 32, 33 which are similar and placed in staggered relation as by being mounted upon rods 34, 35 supported between brackets 36, 37, Fig. 1, 15 for vertical adjustment. The blocks 32, 33 are shown as rounded at 38 at the paper entering ends thereof, which rounded form tapers to a flattened form at 39, see Fig. 4. The blocks 32, 33 may be adjusted for spacing upon the rods 20 34, 35 by loosening set screws 40, 41 and moving the same upon the rods in an obvious manner.

A pair of press rolls 42, 43 are mounted in standard 44 closely adjacent the flattened ends of the blocks 32, 33 so that the paper leaving said 25 blocks is immediately received in the bite of the rolls and pressed to the final form illustrated in Fig. 11.

It will be seen from Fig. 9 that the pleating blocks 32, 33 have their flattened ends 39 lying 30 in such relation as to bring the paper to the final pleating form ready for operation thereon by the press rolls 42, 43.

The pairs of rolls 17, 18, 19, 20, and 42, 43 are driven from each other by inter-engaging gears 35 45, 46, 47, respectively. The roll 12 is driven from the roll 13 in the manner already described. The roll 17 is driven from the roll 12 by means of a sprocket chain 48. The roll 20 is driven from the roll 18 by means of a sprocket chain 49. The 40 roll 42 is driven from the roll 19 by means of a sprocket chain 50.

The brackets 36, 37 are shown as supported from a standard 51.

It is to be understood that the paper taken from the feed roll 52 is preferably previously corrugated and after running through the machine it may be wound upon a storage roll 53.

The belts 23, 24 are preferably formed of helically wound resilient wire and are placed upon 50 the rolls under tension.

The function of the rolls 17, 18 is to give a straight line parallel travel of the belts 23, 24 at the last end of their path in contact with the paper whereby the corrugations of the paper are 55

finally straightened ready for action thereon by the blocks 32, 33.

The rolls 17, 18 may be omitted if desired without rendering the device inoperative.

5 Because the belts 23, 24 are elastic and are under some degree of tension, they will faithfully follow the corrugations of the rolls 17, 18 in passing from converging paths to parallel paths.

The paper may be treated in dry and its percentage of possible stretch will be the difference 10 between the length of the rolls 12, 13 and that of the rolls 19, 20.

Minor changes may be made in the physical embodiment of the invention within the scope of 15 the appended claims without departing from the spirit thereof.

I claim:

1. In a machine of the class described, in combination: a plurality of pairs of upper and lower 20 grooved rolls comprising upper and lower sets; the grooves in the paper-entering pair more widely spaced than and of the same number as the grooves of the succeeding rolls; the grooves of the second and third pairs equally spaced; upper 25 and lower sets of endless bands mounted in alternate of said grooves of the upper and lower sets of rolls; grooved plates to guide said bands from the first to the second pairs of rolls, said grooves converging toward the rolls of said second pair; 30 whereby a sheet led between said upper and lower sets of bands will be given a transversely undulant form progressively decreasing in width to the sec-

ond pair of rolls and straightened to the third pair; means to receive the undulations and progressively guide portions thereof into overlapping relation with other portions thereof; and a press roll to compress the thus formed fold lines. 5

2. A paper pleating member comprising an elongated block, convex at one edge at one end thereof, said edge progressively flattening to a plane surface at its remaining end; said last named end having portions projecting beyond the 10 side surfaces of the block adjacent said plane surface to provide abrupt shoulders at the said projections.

3. In a machine of the class described, in combination: means to deform a moving sheet of 15 paper into longitudinally extending rounded corrugations; upper and lower opposed sets of pleating members at the opposite sides of the path of said moving sheet; each of said members comprising a block set edgewise to said path and the 20 edges thereof each convex at the paper entering end of the sets; said edges progressively flattening to plane surfaced edges at the delivery end thereof and progressively widening to portions projecting beyond the side surfaces of the members providing 25 overlapping shoulders upon the opposed members of the sets; said shoulders on each set spaced from the opposed shoulders a distance substantially equal to the thickness of the sheet, 30 and means to press the resulting pleats.

FRED SCHWARTZ.
